ELECTRICAL CONNECTER

Emil Henry Greibach, Brooklyn, N. Y., assignor
to Sonotone Corporation, New York, N. Y., a
corporation of New York

Application September 1, 1934, Serial No. 742,413

6 Claims. (Cl. 173—332)

This application is a continuation in part of my copending applications Serial No. 556,158 filed August 10, 1931 and Serial No. 701,878 filed December 11, 1933.

This invention relates to electric cord connectors and it is particularly concerned with cord connectors for hearing-aid devices and like instruments in which electrical elements are detachably interconnected by means of flexible cords provided at their ends with connectors for establishing readily detachable, reliable, mechanical and electrical connections between the ends of the cord and the device which they interconnect.

The foregoing and other objects of the invention will be best understood from the following description of exemplifications thereof, reference being had to the accompanying drawing wherein

Fig. 1 is a diagrammatic view of an assembled hearing-aid device embodying the invention;

Fig. 2 is a perspective view of the complete three-prong cord-plug connection to the amplifier of the device;

Fig. 3 is a perspective view of the elements of the cord plug casing;

Figs. 3a and 3b are perspective views of the anchor member and the plug pins;

Fig. 4 is a horizontal sectional view through the cord plug along line 4—4 of Fig. 5;

Fig. 5 is a vertical sectional view of the cord plug along line 5—5 of Fig. 6;

Fig. 6 is a vertical sectional view of the cord plug along line 6—6 of Fig. 5;

Fig. 7 is an elevational view of the detachable cord pin terminal for connecting the cord to the receiver terminals of the device;

Fig. 8 is a transverse sectional view through the receiver casing showing the detachable engagement of the cord pin terminal with the terminal sleeve of the receiver;

Figs. 9 and 10 are detailed views illustrating successive steps in preparing the end of a cord strand for mounting in a pin terminal;

Fig. 11 is a view of the clip plate before it is clamped over the end of a cord strand;

Fig. 12 is a view of the end of a cord strand in completed position before mounting in the pin terminal; and

Figs. 13 and 14 are a sectional and elevational view of a modified form of cord-plug pin terminal.

In Fig. 1 is shown a hearing-aid device comprising a hearing imparting unit in the form of a telephone receiver 10 having an actuating winding 11, a microphone transmitter unit 12 with a control unit 13, a battery 14 and an amplifier 15 with two plug pins 16 engaging battery terminal sleeves 17, the several elements being interconnected by a cord 18 having a transmitter branch with a three-prong plug 19 detachably engaging

the terminals of the transmitter unit 12 a battery branch with a three-prong plug 21 for interchangeably engaging either the amplifier terminals 22 or the battery terminal sleeves 17, and a receiver branch 24 having two loose strand ends 25 provided with plug pin terminals 26 detachably engaging terminal sleeves of the receiver 10 to which the receiver winding 11 is connected.

To secure full utility of the hearing-aid devices, it is not only necessary that the individual parts which participate in the electromagnetic and mechanical actions shall be efficient and satisfactory, but it is also important that the cords and the connecting elements shall be as simple and small as possible but nevertheless be capable of withstanding the continuous handling and permit easy attachment and detachment of the cord ends to the elements of the device. In connection with an amplifying hearing-aid device as

shown in Fig. 1, where the connecting cord has several plug pins in the individual branches, I have devised a novel construction for the plugs, such as plugs 19 and 21 of the cord 18 and the cord connections to the plug and plug pins, the new plug being very small in size, mechanically strong, and simple and cheap in construction and assembly.

A three-contact plug, like contact plug 19, for use to establish the connection of the cord branch either with the amplifier 14 or with the battery 12 is shown in detail in connection with Figs. 4 and 5.

As seen in Figs. 4 and 5, the plug comprises a rectangular casing 110 which is shown enlarged on the drawing; the casing is preferably made of an insulating material, such as molded phenolic condensate, and has formed in its interior a large chamber 111 extending through the full thickness of the casing being bounded

on one side by the rear wall 112 and having opening 113 at the other side, which opening is of the full width and height of the chamber 111. Into this chamber is inserted through the opening 113 an insert 114, the front portion of

which fits the opening 113 and forms a cover 35 enclosing the chamber. This insert 114 has also a rectangular block 115 projecting inwardly for the full thickness of the chamber so that its inner wall abuts against the inner side of the rear wall 112. Thus, when the insert is set into

the chamber, it fills it up and fits firmly therein, its sides resting against the walls of the chamber. The projecting block 115 is of less height than the front wall of the insert 114, leaving a free space in the top of the chamber bounded

on one side by the rear wall 112 of the casing and on the other side by the front cover portion of the insert 114. In the center of the top wall of the casing is provided a perforation 116 for

inserting cord strands 117 of a cord branch, for

instance, branch 80 of Fig. 1. The block 115 is provided with three longitudinal square holes 121 which merge near the bottom into cylindrical portions 122 of a diameter equal to the width 8 of the square. Into these square holes are inserted anchoring sleeves 123 as shown in Fig. 3a having a central square portion 124 and a downward cylindrical portion 125 fitting the square portion 121 and the cylindrical portion 122 of the 10 insert holes, the upper portion 126 of the sleeve being likewise cylindrical like portion 125 and having near its end a groove 127 cut over a small portion along its periphery. The lower half 128 of the sleeve is threaded, and the upper 15 half of the sleeve forms a longitudinal cavity in which the ends of the strands 117 are clamped to secure a good mechanical connection between the sleeve and the strand, and also a good electrical connection between the sleeve and the 20 conducting cord of the strand. The strand used for the cords of these devices are specially made so as to be flexible and yet strong. The usual strands are composed of a core consisting of 25 three or more intertwined flexible conductors made by winding thin copper filaments over a thread so as to have the required conductivity and yet retain great strength. This core has wound thereon additional layers of flexible insulating material, such as silk, and is enclosed 30 by a cover consisting, for instance, of suitably woven silk threads so as to thoroughly protect the conducting core in the interior and at the same time carry the strain imposed on the strands in use by pulling it, etc.

35 To mount the strand end in the plug, the insulating cover of the strand is removed of a portion of its length near the end, as shown in Fig. 9, and this exposed core portion is then folded over the cover portion next to it as shown 40 in Fig. 10. Then a little sheet metal plate 130, shown in Fig. 11, having punched on its surface a few holes so as to provide projecting ridges adapted to grip the strand cover is clamped around the strand end, as shown in Fig. 12, with 45 the folded over core portion to form a sleeve-like clip which is firmly attached to the strand end and grips with its punched projections the surface of the cover, and at the same time makes a good conducting connection with the folded 50 over core elements.

To assemble the plug, the cord with its three strand ends 117 are threaded through perforation 116, while the casing is still empty. The strand ends are usually prepared and provided 55 with the clip before the assembling operation. The clipped strand ends 117 are then inserted into the hollow chamber of the sleeve 126 and clamped within the sleeve by compressing the upper end of the sleeve above the groove 127 so that the strand end is firmly locked in the sleeve and it cannot get out therefrom. A good electrical and mechanical connection between the strand and the anchor sleeve 124 is thus obtained, the anchor sleeve being of metal, such as 60 brass.

65 After the strand ends have thus been secured within the anchor sleeves, the anchor sleeves are pushed into the square holes 121 of the insert block 125 and the insert 124 is inserted into the 70 casing chamber in the way shown in Fig. 8. The underside of the plug has at three points opposite the threaded openings 128 of the sleeves, three openings 133 of the same diameter, with a slightly enlarged recess on the undersurface

75 of the plug arranged to receive the plug pins 134, having a shoulder 135 adapted to fit the recess and a threaded shank portion 137 adapted to be screwed in and to engage the threaded portion 128 of the sleeve.

The plug pin terminals 26 mounted on the ends of loose strands as used, for instance, to connect the receiver strands 25 to the receiver winding 11 are likewise of special construction to secure a good conducting connection between the 20 plugs and the conducting core of the strands, and at the same time also secure a good mechanical connection and prevent pulling out of the strands from the plugs. Each plug pin 26 has at one end a portion 27 shaped to engage 25 the cooperating socket terminal and may vary in shape as shown in Figs. 7, 13 and 14. The interior of the plug pin 26 is hollow and forms a longitudinal cavity 28 open at the end. Into this cavity 28 is inserted the end of the cord 20 strand, after being first prepared as shown in Figs. 9 to 12 and described before.

Before securing the clip on the strand end, a collar 32, as shown in Figs. 7 and 8, is first slipped on the strand end so that when the clip is mounted 30 the collar slides freely back of it. The strand end with the clip mounted thereon is then slipped into the cavity 28 of the plug pin 26. With the clip placed inside, the portion of the pin walls near the opening is compressed or clamped together so as to firmly lock the clip strand end in the cavity and to prevent its being pulled out of it. Preferably, the end portion of the pin near 35 its end has a small cut 33 along a portion of its periphery so that the portion near the end of the pin may be more readily clamped together and caused to lock the clipped strand end firmer in the pin. The collar 32, which has a press fit over the pin end, is then forced in place and the mounting of the plug on the strand end thus completed. The finished unit is extremely simple in manufacture, gives an excellent conducting connection between the conducting core of the strand and the plug pin, provides a strong positive mechanical connection between the plug pin and the cord strand, and has a pleasing neat appearance.

The features of the invention described above are susceptible of many modifications that will suggest themselves to those skilled in the art.

I claim:

1. In a detachable terminal connection of a cord for an electric instrument subject to handling comprising, in combination with the terminal end of a flexible cord strand having a flexible insulating cover and a flexible conducting core having an exposed end portion folded over the exterior of said cover, an elongated solid conducting plug member having an exposed contact portion on its outward end and a longitudinal deformed cavity at its inward end surrounding and compressing the strand terminal end, and a cover enclosing the inward end of said plug member and the adjoining portion of said strand.

2. In a detachable terminal connection of a cord for an electric instrument subject to handling comprising, in combination with the terminal end of a flexible cord strand having a flexible insulating cover and a flexible conducting core having an exposed end portion folded over the exterior of said cover, a clip of relatively soft sheet metal clamped around said folded strand terminal end and gripping said cover and folded core, an elongated solid conducting plug member having an exposed contact portion on its outward

end and a longitudinal deformed cavity at its inward end surrounding and compressing the strand terminal end, and a cover enclosing the inward end of said plug member and the adjoining portion of said strand.

3. In a detachable terminal connection of a cord for an electric instrument subject to handling comprising, in combination with the terminal end of a flexible cord strand having a flexible insulating cover and a flexible conducting core having an exposed end portion folded over the exterior of said cover, a longitudinally extending plug casing of insulating material having a hollow chamber with an opening on one side thereof, an inward wall having a strand opening, and an outward wall having a terminal opening, said strand terminal end extending through said strand opening into said chamber, an insert of insulating material having an external wall enclosing said chamber opening to complement the exterior of said casing and a block extending into the interior of said chamber having a perforation aligned with said terminal opening, a conducting anchor member slidably fitting into said perforation and locked therein against rotation and movement in outward direction, the inward end of said anchor member having a longitudinal cavity surrounding and holding grippingly clamped the strand terminal end, and an elongated plug terminal member having an exposed outward contact portion and an inward portion for detachable locking engagement with the outward end of said anchor member through said terminal opening for locking said insert in said casing, said anchor member and the connection thereof with said strand and said terminal member being entirely enclosed by said casing.

4. In a detachable terminal connection of a cord for an electric instrument subject to handling comprising, in combination with the terminal end of a flexible cord strand having a flexible insulating cover and a flexible conducting core having an exposed end portion folded over the exterior of said cover, a clip of relatively soft sheet metal clamped around said folded strand terminal end and gripping said cover and folded core, a longitudinally extending plug casing of insulating material having a hollow chamber with an opening on one side thereof, an inward wall having a strand opening, and an outward wall having a terminal opening, said strand terminal end extending through said strand opening into said chamber, an insert of insulating material having an external wall enclosing said chamber opening to complement the exterior of said casing and a block extending into the interior of said chamber having a perforation aligned with said terminal opening, a conducting anchor member slidably fitting into said perforation and locked therein against rotation and movement in outward direction, the inward end of said anchor member having a longitudinal cavity surrounding and holding grippingly clamped the strand terminal end, and an elongated plug terminal member having an exposed outward contact portion and an inward portion for detachable locking engagement with the outward end of said anchor member through said terminal opening for locking said insert in said casing, said anchor member and the connection thereof with said strand and said terminal member being entirely enclosed by said casing.

5. In a detachable terminal connection of a cord for an electric instrument subject to handling comprising, in combination with terminal ends of two or more flexible cord strands, each having a flexible insulating cover, and a flexible conducting core having an exposed end portion folded over the exterior of said cover, a longitudinally extending plug casing of insulating material having a hollow chamber with an opening on one side thereof, an inward wall having a strand opening, and an outward wall having two terminal openings, said strand terminal ends extending through said strand opening into said chamber, an insert of insulating material having an external wall enclosing said chamber opening to complement the exterior of said casing and a block extending into the interior of said chamber having perforations aligned with said terminal openings, conducting anchor members slidably fitting into said perforations and locked therein against rotation and movement in outward direction, the inward ends of said anchor members having longitudinal cavities surrounding and holding grippingly clamped said strand terminal ends, and elongated plug terminal members having exposed outward contact portions and inward portions for detachable locking engagement with the outward ends of said anchor members through said terminal openings for locking said insert in said casing, said anchor members and the connection thereof with said strands and said terminal members being entirely enclosed by said casing.

6. In a detachable terminal connection of a cord for an electric instrument subject to handling comprising, in combination with terminal ends of two or more flexible cord strands, each having a flexible insulating cover, and a flexible conducting core having an exposed end portion folded over the exterior of said cover, clips of relatively soft sheet metal clamped around said folded strand terminal ends and gripping the associated cover and folded core portions, a longitudinally extending plug casing of insulating material having a hollow chamber with an opening on one side thereof, an inward wall having a strand opening, and an outward wall having two terminal openings, said strand terminal ends extending through said strand opening into said chamber, an insert of insulating material having an external wall enclosing said chamber opening to complement the exterior of said casing and a block extending into the interior of said chamber having perforations aligned with said terminal openings, conducting anchor members slidably fitting into said perforations and locked therein against rotation and movement in outward direction, the inward ends of said anchor members having longitudinal cavities surrounding and holding grippingly clamped said strand terminal ends, and elongated plug terminal members having exposed outward contact portions and inward portions for detachable locking engagement with the outward ends of said anchor members through said terminal openings for locking said insert in said casing, said anchor members and the connection thereof with said strands and said terminal members being entirely enclosed by said casing.
